WINTHROP K. HOWE, OF ROCHESTER, NEW YORK, ASSIGNOR TO GENERAL RAILWAY SIGNAL COMPANY, OF ROCHESTER, NEW YORK.

TRAIN CONTROL.

Application filed November 17, 1924. Serial No. 750,374.

This invention relates to automatic train control systems, and more particularly to a system incorporating means for automatically detecting failure of the driving mechanism of the car-carried apparatus connected to the car wheels.

In the type of train control system commonly known as the train speed control or permissive speed system, some suitable speed responsive device is included in the car-carried equipment, and is suitably driven from the axles of the vehicle in accordance with the progress of the vehicle along the trackway. If the driving mechanism of this speed responsive device should become broken or disconnected, the device would indicate a zero speed, and no restrictive brake application would be imposed under any traffic conditions, with the result that the train control system would become ineffective.

With the above and other considerations in mind, it is proposed in accordance with the present invention to provide means for checking the operation of the driving mechanism for the car-carried speed responsive device, and more specifically, to provide means for imposing an automatic brake application if the speed responsive device is not in operation within a given time interval after an influence corresponding to caution or danger traffic conditions is received. Other objects, characteristics and advantageous features of the present invention will become apparent as the description thereof progresses.

In the drawings, Figure 1 represents a simplified type of train speed control system embodying the checking device of the present invention; and

Fig. 2 represents a modification of the starting circuit used in the system shown in Figure 1.

It is understood that the checking apparatus for the speed responsive device comprising the present invention might be used in connection with any form of automatic train control system of the permissive speed type, but for the purpose of illustration, an extremely simple form of permissive speed system embodying the well known continuous inductive method of influence communication has been shown. As train control sys-

tems of this type are well known to those skilled in the art, a rather brief description of the construction and operation of the train control system will be given.

Referring first to the trackway equipment, the track rails 1 have been shown divided into the usual blocks by the insulating joints 2, the block I and the ends of the two adjacent blocks H and J having been shown. The usual track relays 3 are connected across the track rails at the entrance ends of the blocks, these relays being energized by the track batteries 4 which are connected across the track rails at the exit ends of the blocks, reference being had to the normal direction of traffic as indicated by the arrow. The track relays 3 operate the movable contact fingers 5 and 6 which control a circuit for impressing an alternating control current across the track rails at the entrance end of each block from the transmission line 7, this circuit including the transformers 8 and 9 as clearly shown.

The usual wayside semaphore signals Z have been shown in a conventional manner at the entrance end of each block, it being understood that any other type of wayside signals may be used.

It is obvious that if a train is located in a given block its wheels and axles will shunt the track battery 4 and the secondary winding of the transformer 9, causing the track relay 3 associated with this block, to be de-energized and the control current to be cut off in the track rails behind the train. The de-energization of the track relay will cause the control current to be cut off from the track rails in the block next in the rear of the given block by the retraction of the contact fingers 5 and 6 of this relay.

A railway vehicle has been conventionally represented in the block H by the wheels and axles 10, this vehicle being provided with the usual inductive receiving coils 11 mounted in inductive relation to the track rails 1, in front of the leading axle of the vehicle. These receiving coils 11 are connected in such a manner that currents induced therein by the control current flowing in opposite directions in the two track rails will be additive. The receiving coils 11 are connected to the input circuit of a suitable amplifier, pref-

erably of the audion tube type, which has been conventionally represented at A; the output of this amplifier being connected to the main relay MR as shown. This main relay 5 MR is provided with two movable contact fingers 12 and 13, which contacts are included in control circuits as hereinafter described. Referring now to the car-carried equipment, a drive shaft 14 is provided and is 10 geared or otherwise suitably driven from an axle of the vehicle. This shaft 14 carries a worm 15 and a speed responsive device. The speed responsive device may take any suitable form, but in the embodiment chosen 15 for the purpose of illustration, a simplified speed responsive device has been shown, taking the form of the centrifuge G. This centrifuge comprises a fixed collar 16 and a movable collar 17 on the shaft 14, urged apart 20 by the spring 20; the collar 17 being drawn downwardly as the speed of rotation of the shaft 14 increases by a centrifugal force acting on the weights 19 which are connected to the collars 16 and 17 by the links 18. The 25 collar 17 engages an arm 21 fixedly secured to a speed shaft 22 as clearly shown, so that the shaft 22 is rocked in proportion to the speed at which the vehicle is traveling. It should be noted that the worm 15 and the 30 fixed collar 16 are intimately associated, being preferably made integral, so that the possibility of a failure of the driving mechanism between the worm 15 and the centrifuge G is very remote. 35 The worm 15 operates a distance shaft 23 through a gear 24, a shaft 25 and a gear train 26, carried by magnetically operated arm 27 as shown. The arm 27 is held in the disengaged position by means of the cam 40 starter magnet CS, and when this magnet is de-energized the spring 28 places the arm 27 in a position such that the end gear 29 of the gear train 26 engages a mutilated gear 30 which is secured to the distance shaft 23. The 45 distance shaft 23 is returned to its normal position upon the disengagement of the gears 29 and 30 by means of a spring 31. Suitable means are provided for closing a 50 circuit in response to the initial movement of the distance shaft 23, and in the embodiment shown, a distance cam 32 is provided on the shaft 23 and operates a pair of resilient contact fingers 34 which are biased to their open position, the cam 32 being designed to close 55 these contact fingers as soon as the distance shaft 23 starts to rotate.

The vehicle speed may be controlled in any 60 suitable manner, but in the system shown, means are provided for controlling the vehicle speed in accordance with the distance of travel from a point at which a restrictive impulse is received from the trackway; it being understood that any one of a number of well known train speed control means might 65 be used. The speed-distance or permissive

speed feature is provided by means of a permissive speed cam 33 secured to the shaft 23 and acting to operate one end of a floating lever 35, the other end of which is moved by an arm 36 fixedly secured to the speed shaft 70 22. It is evident that the movement of an intermediate point on the floating lever 35 is proportional to a function of the vehicle speed and its distance of travel from the point at which the distance shaft 23 is initiated. The 75 floating lever 35 operates a contact sector 37 through a link 38, this contact sector 37 being biased by a spring 39. The sector 37 operates the resilient contact fingers 40, which are normally biased to their open position, and it 80 is evident that as the vehicle speed increases, the contact sector 37 will be swung in a clockwise direction by the arm 36, the floating lever 35 and the link 38, causing the contact fingers 40 to open at some predetermined speed 85 depending on the position of the permissive speed cam 33 and the construction of the contact sector 37.

A check relay CR is provided and is of a suitable slow acting type, that is, once energized, it will not retract its contact finger 41 for a given period of time after its de-energization. This slow acting feature may be accomplished by providing a copper sleeve around the relay core to sustain the flux therein, or by a dash pot, or other suitable mechanical means. 90

A starting relay SR of any suitable type is provided, its energizing circuit including a push button PB as shown. This starting relay 100 15 of the slow drop-away type, this feature being secured by a dash pot and a flexible arm combination. 95

The automatic control of the brakes of the vehicle may be effected in any suitable manner and by means of any suitable automatic brake control device. As the automatic initiation of a brake application is usually effected by means of some suitable air valve, an electro-pneumatic valve EPV has been shown in the drawings, it being understood that this electro-pneumatic valve acts in some suitable manner to initiate a brake application upon the de-energization of a circuit through its windings. 105 110 115

Operation.—All of the apparatus in the drawings has been shown in its normal operating condition, that is, the positions of the various devices are such as is assumed with a train running at a speed below the maximum but above the minimum permissive limit, and under clear traffic conditions ahead. The letters B and C have been used to indicate the opposite poles of a suitable source of energy, preferably a storage battery. 120 125

Referring briefly to the operation of the simplified train control system shown, assuming a train to be proceeding under clear traffic conditions, that is, with no other train in the block in which it is located or in the 130

next block in advance, train control current flows in the track rails and induces currents in the receiving coils 11; these currents are amplified by the amplifier and energize the 5 main relay MR, attracting its contact fingers 13 and 12 and closing their respective front contacts. An energizing circuit for the electro-pneumatic valve EPV is now completed which circuit may be traced as 10 follows:—from the battery terminal B, through wire 47, contact finger 41 and front contact of the check relay CR, wires 49 and 51, contact fingers 40 of the contact sector 37, wires 52, contact finger 44 and back contact 15 of the push button PB and wire 53 through the winding of the electro-pneumatic valve EPV to the battery terminal C. The cam starter magnet CS is also maintained energized through contact finger 13 20 of the main relay MR and a circuit which is obvious from the drawings. With the cam starter magnet CS energized, the distance shaft 23 will be maintained in its normal position, as shown, by the spring 31.

25 Assume now that a train equipped with the system shown enters a block in which caution or danger traffic conditions exist, that is, a block in which another train is located or the first block in the rear of such 30 occupied block. Under these conditions, the train control current is cut off from the track rails and the receiving coils 11 do not have currents induced therein, causing the de-energization of the main relay and the 35 consequent retraction of its contact fingers 12 and 13. The retraction of the contact finger 13 breaks the energizing circuit to the cam starter magnet CS, thus allowing the spring 28 to engage the gear train 26 and 40 the mutilated gear 30 and the distance shaft 23 is thereby rotated. The retraction of the contact finger 12 of the main relay MR de-energizes the check relay CR, which, after a period of time, retracts its contact finger 41; 45 but before this contact finger 41 has been retracted, the distance cam 32 will have closed its contact fingers 34, shunting the contact finger 41 through the wires 48 and 50, so that the de-energization of the check 50 relay CR has no effect under these conditions.

The distance shaft 23 is now rotated in accordance with the progress of the vehicle, and the permissive speed cam 33 moves the 55 upper end of the floating lever 35 to the left, so that the train speed must be reduced to bring the lower end of the lever 35 to the right in order to prevent the opening of the contact finger 40 of the contact sector 37 60 and a consequent de-energization of the electro-pneumatic valve EPV which would cause an automatic brake application.

The distance shaft 23 continues to rotate until the mutilated portion of the gear 30 65 is opposite the gear 29, and at this point a

minimum speed restriction is imposed by the cam 33 and the train may proceed at this limited speed only until the main relay MR is again energized in response to more favorable traffic conditions. 70

Referring now more particularly to the operation of the check for the driving mechanism which comprises the present invention, assume that the driving mechanism for the shaft 14 becomes broken or disengaged 75 from the axle of the vehicle or that for any other reason the cam shaft 23 fails to move when it should. When the train enters a caution or danger block with the drive shaft disengaged, the main relay MR will be de- 80 energized, causing a de-energization of the check relay CR and the cam starter magnet CS as described above. The distance shaft 23 will not be rotated because of the failure of the driving mechanism, and for this reason the contact fingers 34 of the distance cam 32 will remain open. After a given time interval, the check relay CR will retract its contact finger 41, breaking the energizing circuit to the electro-pneumatic valve EPV 85 traced above, and causing an automatic brake application bringing the train to a stop. The engineer may now repair the driving mechanism or, preferably, render the automatic brake control apparatus in- 90 active by the operation of a suitable cut-out device, such as a switch, which may be provided in connection with the automatic train control system for connecting the wire 53 with the battery terminal B and so main- 95 taining the electro-pneumatic valve energized; this cutout device preferably being protected against unauthorized use by a sealed casing or other suitable means. 100

In a continuous inductive train control system, a train may come to a stop under clear traffic conditions, and while at a stop, the traffic conditions may change to caution or danger by reason of the entrance of a train, the breaking of a track rail, the opening of a 105 switch, or other hazards in the block in which the stopped train is located, or in the first block in advance thereof. Under these conditions, the main relay MR is de-energized and retracts its contact fingers 12 and 13, de- 110 energizing the check relay CR and the cam starter magnet CS. After a time interval, the check relay CR drops its contact finger 41, but, as the train is not moving, the contact fingers of the distance cam 32 have not been 115 closed and the circuit to the electro-pneumatic valve is therefore broken, causing an automatic brake application and holding the train stationary. In order that the train may be released from this automatic brake application and may proceed, a separate manual means is provided for energizing the check 120 relay CR which means is protected against misuse as hereinafter described. The push button PB is depressed by the engineer caus- 125 130

ing an energization of the starting relay SR through the contact finger 62 of the push button and a circuit which is obvious from the drawings. When energized, the starting relay SR attracts its contact finger 42, closing an energizing circuit for the check relay CR through wire 46 as clearly shown, the push button being maintained depressed until the check relay CR has attracted its contact finger 41, after which the push button PB is released. An energizing circuit for the electro-pneumatic valve EPV is now completed through the contact finger 41 of the check relay CR, which circuit has been traced, and this circuit is maintained for a time interval equal to the sum of the drop away periods of the two relays CR and SR, both of which relays are slow acting as hereinbefore described. This time interval is arranged to be long enough to energize the electro-pneumatic valve, to permit the engineer to release the brakes from the automatic brake application and to allow the train to get in motion. As soon as the train is in motion, the distance cam 32 will close its contact fingers 34, shunting the contact finger 41 of the check relay CR and completing an energizing circuit for the electro-pneumatic valve EPV. The train may now proceed under the control of the permissive speed cam 33 as described above.

It should be noted that the engineer may not abuse the use of the starting relay SR by fastening or holding the push button PB in its depressed condition, as this push button is provided with a contact finger 44 which is included in the energizing circuit for the electro-pneumatic valve, this contact being open when the push button is depressed and so maintaining the electro-pneumatic valve de-energized until the push button is released.

In Figure 2, an alternative scheme has been shown for re-energizing the check relay CR and so allowing the train to proceed after this relay has been de-energized by reason of a change to danger or caution traffic condition while the train is at a stop. In this modification, the starting relay SR and the push button PB are omitted, and an air operated switch S is provided. This switch consists of a piston 54, carried in a cylinder 55 and operating an insulated contact member 56 which is adapted to engage two stationary contact fingers conventionally represented by the arrows 57 and 58, when air pressure is applied to the cylinder 55. The piston 54 is returned to a position to open the contacts 56, 57 and 58 by means of a spring 59 when the air pressure in the cylinder 55 has diminished below a predetermined value. The cylinder 55 is connected by a suitable pipe 60 to the "brake cylinder pipe" of the well known ET air brake equipment or other suitable connections are made so that pressure is applied to the cylinder 55 and the contacts 56, 57 and 58 are closed only when the brakes have been applied

on the engine and tender. The contacts 57 and 58 are connected to the check relay and to the battery terminal B as shown, so that the check relay CR is energized through these contacts when the engine and tender brakes are applied. If the engine and tender brakes are maintained applied until the instant which the train is to be started, the check relay CR is maintained energized while the train is stationary even though the main relay MR is de-energized. If, however, the engine and tender brakes have been released, the engineer will apply these brakes just before releasing all of the brakes to start the train. As the train starts, the brakes are released, and the circuit through the air switch S is broken, de-energizing the check relay CR, but before the check relay has retracted its contact finger 41, the distance cam 32 closes its contact fingers 34, so maintaining the circuit to the electro-pneumatic valve closed, and the train may proceed under the restriction of the permissive speed cam 33 as described above. If the train exceeds the permissive speed limit set up by the cam 33 while traveling under caution or danger control, an automatic brake application results as described above, and this application causes the air switch S to close its contacts 56, 57 and 58, re-energizing the check relay CR. As the contacts 34 of the distance cam 32 are closed while the train is under danger or caution control, this re-energization of the check relay CR has no effect.

If the driving mechanism for the car-carried equipment embodying the air switch S shown in Figure 2 becomes broken or disengaged and the train enters a caution or danger block, the check relay CR will be de-energized, by the de-energization of the main relay MR, and, as the contacts 34 of the distance cam 32 do not close, the electro-pneumatic valve EPV is de-energized by the retraction of the contact finger 41 of the check relay. The de-energization of the electro-pneumatic valve EPV causes an automatic brake application, and as the air is admitted to the "brake cylinder pipe" of the well known ET equipment, the air switch S connected to this pipe is closed, re-energizing the check relay CR and the electro-pneumatic valve EPV, thus permitting the release of the brakes. As soon as the brakes are released, however, the air switch S will re-open, de-energizing the electro-pneumatic valve, thus causing another automatic brake application. It is thus evident that with the driving mechanism broken or otherwise disengaged, an automatic brake application will result under caution or danger conditions, and that although this brake application can be subsequently released, a second automatic brake application will follow if the brakes are released, and so on, thus imposing successive automatic brake applications and, if the train be not stopped, at least

limiting the progress of the train to a safe speed. As stated, de-energization of EPV produces an automatic brake application, which in turn, through switch S, re-energizes 5 relay CR to cause energization of EPV and permit the engineer to release the brakes and to retain the brakes released until relay CR has released and the consequent de-energization of EPV has caused a new automatic brake 10 application.

It is obvious that in the modified system shown in Figure 2, no protection against misuse is needed, it being assumed that a safe control is imposed if the brakes are applied, 15 and for this reason the energizing circuit for the electro-pneumatic valve EPV in a system employing this modification would be connected directly to the contact finger 40 of the contact sector 37 through the wire 52 (PB 20 being omitted).

As the drive mechanism checking device comprising the present invention has been described in a rather specific manner and in connection with one specific type of train control 25 system, it should be clearly understood that this device may be modified or combined with other equipment, and further that this device would be employed with any suitable type of permissive speed train control system without 30 departing from the spirit of the present invention as defined by the appended claims.

What it is desired to secure by Letters Patent is:—

1. In an automatic train control system, 35 vehicle carried control means including elements adapted to be driven in accordance with the progress of the vehicle, means for setting said control means in operation, in response to an influence corresponding to unfavorable 40 traffic conditions ahead, means for imposing an automatic brake application if said driven elements are not in operation within a predetermined period of time after said influence is received, and means effective only if the 45 brakes are applied, for preventing said automatic brake application.

2. In an automatic train control system, vehicle carried apparatus comprising a control means responsive to influences corresponding to traffic conditions ahead, a restrictive speed device having an element driven in accordance with the motion of the vehicle, said restrictive speed device being initiated by said control means under unfavorable traffic 55 conditions ahead, means for causing an automatic brake application if said restrictive speed device is not in operation within a predetermined period of time after said control means has received an influence corresponding to unfavorable traffic conditions 60 ahead, and means for temporarily releasing the vehicle from said automatic brake application.

3. In an automatic train control system, 65 vehicle carried control means responsive to

influences corresponding to traffic conditions ahead, a restrictive speed device having a distance element adapted to be driven at times in accordance with the motion of the vehicle, said distance element being initiated by said control means under unfavorable traffic conditions ahead, means for causing a brake application if said distance element has not been initiated within a predetermined period of time after the reception of an influence corresponding to unfavorable traffic conditions ahead, and manually operable means for permitting the release of said automatic brake application for a limited period of time. 75

4. In an automatic train control system, 80 vehicle carried brake control apparatus comprising a brake applying device, a restrictive speed device including an element driven at times in accordance with the progress of the vehicle, a main relay controlled in response to influences corresponding to traffic conditions ahead, means controlled by the de-energization of said main relay for initiating said driven element and controlling said brake applying device by said restrictive 85 speed device under unfavorable traffic conditions, a control relay actuated by said main relay and acting to operate said brake applying device if said driven element has not been initiated within a predetermined period of 90 time after the de-energization of said main relay, and means for temporarily preventing the operation of said brake applying device by said control relay. 95

5. In an automatic train control system, 100 vehicle carried brake control apparatus comprising a brake applying device, a restrictive speed device including an element driven at times in accordance with the progress of the vehicle, said restrictive speed device normally 105 controlling said brake applying device, a main relay controlled in response to influences corresponding to traffic conditions ahead, means controlled by said main relay for initiating said driven element of said restrictive speed device under unfavorable traffic conditions ahead, means for actuating said brake applying device independently of said restrictive speed device if said driven element does not operate in response to the control 110 of said main relay, and manually actuatable means for temporarily placing said brake applying device under the control of said restrictive speed device. 115

6. In an automatic train control system, 120 vehicle carried brake control apparatus comprising a brake applying device, a restrictive speed device including an element driven at times in accordance with the progress of the vehicle and normally controlling said brake 125 applying device, a control means for connecting the driven element of said restrictive speed device to a driving member in response to control influences corresponding to unfavorable traffic conditions ahead, means for 130

causing said brake applying device to operate independently of said restrictive speed device if said driven element is not initiated in response to the operation of said control means, and means, actuatable only if the vehicle brakes are applied, to return the control of said brake applying device to said restrictive speed device for a limited period of time.

7. In an automatic train control system, vehicle carried apparatus comprising a restrictive speed device including an element adapted to be driven in accordance with the progress of a vehicle and acting to impose increasingly restrictive speed limits when initiated; a control device for initiating the operation of said driven element in response to influences corresponding to unfavorable traffic conditions ahead, a relay controlled by said control device and acting to impose an automatic brake application if said driven element does not operate in response to the operation of said control device, and additional means for operating said relay to release said automatic brake application for a limited period of time if the vehicle brakes are applied.

8. In an automatic train control system, vehicle carried apparatus comprising a restrictive speed device including an element adapted to be driven in accordance with the progress of a vehicle and acting to impose increasingly restrictive speed limits when initiated; a main relay for initiating the operation of said driven element in response to influences inductively received from the trackway and corresponding to unfavorable traffic conditions ahead, a control relay operated by said main relay and acting to impose an automatic brake application if said driven element does not operate in response to said main relay and means including an air switch for preventing said automatic brake application if the vehicle brakes are applied and for a limited period of time after the brakes are released.

9. In an automatic train control system, vehicle carried control apparatus comprising a main relay controlled by influences corresponding to traffic conditions ahead, a control relay controlled by said main relay, a restrictive speed device driven in accordance with the motion of the vehicle under unfavorable traffic conditions ahead, a normally energized brake applying device adapted to control the vehicle brakes when deenergized, circuits for energizing said brake applying device having a common portion including contacts operated by said restrictive speed device in series with parallel portions one of which includes a contact of said control relay, and the other of which includes contacts closed only when said restrictive speed device is being driven, and means for temporarily energizing said control relay when said main relay is de-energized.

10. In an automatic train control system, vehicle carried control apparatus comprising a main relay controlled by influences corresponding to traffic conditions ahead, and de-energized under unfavorable traffic conditions, a slow acting control relay controlled by said main relay and arranged to open its contacts a predetermined time after said main relay is de-energized, a restrictive speed device initiated by the de-energization of said main relay and having an element driven from the vehicle wheels when initiated, a normally energized brake applying device adapted to apply the vehicle brakes when de-energized, means for controlling the energization of said brake applying device in accordance with the operation of said restrictive speed device, further means including contacts of said control relay for causing the de-energization of said brake applying device independently of said restrictive speed device if said driven element of said restrictive speed device is not initiated a predetermined time after said main relay is de-energized, and means for energizing said control relay to re-energize said brake applying device if the vehicle brakes are applied.

11. In an automatic train control system, vehicle carried brake control apparatus comprising a brake applying device, a restrictive speed device including an element driven at times in accordance with the progress of the vehicle, said restrictive speed device normally controlling said brake applying device, a main relay controlled in response to influences corresponding to traffic conditions ahead, means controlled by said main relay for initiating said driven element of said restrictive speed device under unfavorable traffic conditions ahead, means for actuating said brake applying device independently of said restrictive speed device if said driven element does not operate in response to the control of said main relay, and manually actuatable means for temporarily placing said brake applying device under the sole control of said restrictive speed device.

12. In a train control system, car-carried apparatus including, a brake applying device, traffic controlled means for initiating said device, a restrictive speed device controlled at times in accordance with the progress of the train and effective at times to initiate said brake applying device, and an element driven in accordance with the distance traveled by the train for preventing said initiation of said device during train movement, only if its drive means is in operative condition.

13. In a train control system, car-carried apparatus including, a brake applying device, traffic controlled means for initiating said device, and an element driven in accordance with the progress of the train for closing a shunt around said traffic controlled

means for preventing said initiation of said device during train movement, only if its drive means is in operative condition.

14. In a train control system, car-carried apparatus including, a brake applying device, traffic controlled means for initiating said device, an element driven in accordance with the amount of movement of the train for preventing said initiation of said device during train movement, only if its drive means is in operative condition, and means for temporarily preventing initiation of the brake applying device when said drive means is inoperative.

15. In a train control system, car-carried apparatus including, a brake applying device, traffic controlled means for initiating said device, an element driven in accordance with the amount of movement of the train for closing a shunt around said traffic controlled means for preventing said initiation of said device during train movement, only if its drive means is in operative condition, and means for temporarily preventing initiation of the brake applying device when said drive means is inoperative.

In testimony whereof I affix my signature.
WINTHROP K. HOWE.
